BABY'S SLEEPING BAG

Evelyn Lehigh, Mamaroneck, N. Y.

Application May 20, 1947, Serial No. 139,149

Term of patent 14 years

(Cl. D92—2)

To all whom it may concern:

Be it known that I, Evelyn Lehigh, a national of the Dominion of Canada, residing at Mamaroneck, in the county of Westchester and State of New York, have invented a new, original, and ornamental Design for a Baby's Sleeping Bag, of which the following is a specification, reference being had to the accompanying drawing, forming part thereof, and wherein

Fig. 1 is a front elevational view of a baby's sleeping bag, showing my new design;

Fig. 2 is a rear view thereof showing one of the sleeve ends in closed position, and

Fig. 3 is a fragmentary front view of one of the sleeve ends in closed position.

The characteristic features of my design reside in the combination on the sleeping bag disclosed of the continuous binding strip on the outer edges and the integral pointed sleeve ends, the

front panels of which ends are folded back and stitched in open position; the rear panels of the sleeve ends being folded back upon the front panel ends in closed position, all as shown.

I claim:

The ornamental design for a baby's sleeping bag, substantially as shown and described.

EVELYN LEHIGH.
